(57) **CLAIM**

The ornamental design for a rod attachment extension, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of a rod attachment extension in accordance with the new design;

FIG. 2 is a top plan view of the rod attachment extension of FIG. 1;

FIG. 3 is a bottom plan view of the rod attachment extension of FIG. 1;

FIG. 4 is a front end plan view of the rod attachment extension of FIG. 1;

FIG. 5 is a back end plan view of the rod attachment extension of FIG. 1;

FIG. 6 is a first side plan view of the rod attachment extension of FIG. 1; and,

FIG. 7 is a second side plan view of the rod attachment extension of FIG. 1.

1 Claim, 5 Drawing Sheets
